ULTRASONIC NEBULIZER

Cleafe A. Best, Jr., Littleton, Colo., assignor to J. J. Monaghan Company, Inc., Denver, Colo., a corporation of Colorado

Filed Apr. 10, 1968, Ser. No. 11,390

Term of patent 14 years

Int. Cl. D23—01; D24—02

U.S. Cl. D83—1

FIG. 3.

FIG. 5.

FIG. 4.

FIGURE 4 is a rear elevation wherein both the supply bottle and patient supply hose have been removed and the supply bottle hanger has been swung to one side;

FIGURE 5 is a bottom plan view wherein both the supply bottle and patient supply hose have been deleted;

The right side elevation is substantially a mirror image of the left side elevation shown in FIGURE 1, except for the appearance of the small power cord on the right front of the unit that is shown in FIGURE 2.

I claim:

The ornamental design for an ultrasonic nebulizer, as shown and described.
